UNITED STATES PATENT OFFICE.

FRANCIS H. McCORMICK, OF GLEN ELLYN, ILLINOIS, ASSIGNOR TO EDISON ELECTRIC APPLIANCE COMPANY, INCORPORATED, OF CHICAGO, ILLINOIS, A CORPORATION OF NEW YORK.

DESIGN FOR AN ELECTRIC HEATER.

Application filed June 14, 1927. Serial No. 22,423. Term of patent 14 years.

To all whom it may concern:

Be it known that I, FRANCIS H. McCORMICK, a citizen of the United States, residing at Glen Ellyn, in the county of Du Page, State of Illinois, have invented a new, original, and ornamental Design for Electric Heaters, of which the following is a specification, reference being had to the accompanying drawing, forming a part thereof.

The single figure of the drawing is a front view of an electric heater embodying my new design.

I claim:

The ornamental design for an electric heater substantially as shown.

In witness whereof, I have hereunto set my hand this tenth day of June 1927.

FRANCIS H. McCORMICK.
